UNITED STATES PATENT OFFICE.

EDWARD W. MARVEL, OF PHILADELPHIA, PENNSYLVANIA, ASSIGNOR TO WILLIAM H. HOLLAR, OF PHILADELPHIA, PENNSYLVANIA.

ELECTRICALLY-CONTROLLED LOCK.

No. 902,244.

Specification of Letters Patent.

Patented Oct. 27, 1908.

Application filed May 12, 1908. Serial No. 432,540.

To all whom it may concern:

Be it known that I, EDWARD W. MARVEL, of Philadelphia, in the State of Pennsylvania, have invented a certain new and useful Improvement in Electrically-Controlled Locks, whereof the following is a specification, reference being had to the accompanying drawings.

My improvement is particularly applicable to locks for safes or vaults comprising a rotary shaft which is required to be turned to a definite extent; for instance, said rotary shaft may be the tumbler arbor of a combination or permutation lock or the winding arbor of a time lock.

Although in a combination or permutation lock, such a rotary shaft is required to be turned alternately in opposite directions, and in a time lock, such a rotary shaft is required to be turned in but one direction; in either case, my improvement comprises the combination with a winding motor local to the lock, of an indicator motor local to means for controlling both motors, and remote from the lock; both motors being so electrically connected as to be operated synchronously, so that the operator manipulating said controlling means may ascertain from the manifestation of said indicator, the precise position of rotation of the lock shaft being turned by the winding motor.

My invention comprises the various novel features of construction and arrangement hereinafter more definitely specified and claimed.

In the drawings; Figure I, is a diagram showing an arrangement of the electrical connections of my invention for operating a combination lock. Fig. II, is a front elevation of the winding motor and mechanism operatively connecting it with the lock arbor. Fig. III, is an end view of the winding mechanism shown in Fig. II. Fig. IV, is a front elevation of the indicator motor and mechanism connected therewith. Fig. V, is a fragmentary sectional view of one of the divided clutch shafts, taken on the line V, V, in Fig. IV.

Referring to Fig. I; the parts indicated below the line X—X, are located within the safe in which the lock is employed, and the other parts are exterior thereto. The electric winding motor comprising the field 1, and the armature 2, is arranged to turn the lock arbor 3, by the wheel 4. The direction of rotation of said armature 2, is constant,

but said lock arbor 3, may be turned alternately in opposite directions by mechanical connection therewith, such connection being determined by the clutch magnets 6 and 7, 60 which are local to said winding motor. The electric indicator motor comprising the field 9, and the armature 10, is arranged to actuate the indicator dial 12, in synchronism with the rotation of the wheel 4; the direction of rotation of said dial 12, being determined by the clutch magnets 13 and 14, which are local to said indicator motor. The current is supplied through the leads 16 and 17, which connect through the fuse 70 block 18, with the double-pole switch 19, whereby the current supply may be entirely cut off from the apparatus. The leads 21 and 22, extend from said knife switch 19, to the double-pole push button 23, whereby 75 said lead 22, is connected by the lead 24, with the field 9, of the indicator motor which is connected in shunt with its armature 10, by the lead 25. Said armature is connected by the lead 26, in series relation 80 with the field 1, of the winding motor which is connected by the lead 27, in shunt relation with its armature 2, and said armature is connected by the lead 28, through the resistance 29, and said push button 23, with 85 the lead 21. Said push button 23, is normally spring pressed to break the circuit through the leads 24, and 28, but is pressed by the operator to close the circuits as shown. The switch 30, which conveniently 90 comprises an oscillatory knife blade, is employed to alternately actuate the right hand and left hand clutch magnets local to said motors. Said right hand clutch magnet 14, 95 of the indicator mechanism, and the right hand clutch magnet 7, of the winding mechanism being connected in series relation by the lead 31, branching from the supply lead 22, to the switch 30, the lead 32, extending from said switch 30, to the magnet 14; the lead 33, extending from said magnet 14, to the magnet 7; and thence, by the lead 37, 100 through the resistance coil 38, to the supply lead 21. Said left hand clutch magnet 13, of the indicator mechanism and the left hand clutch magnet 6, of the winding mechanism may be connected in series relation when the switch blade 30, is shifted to the left to close the circuit from the lead 31, through the lead 39, to the clutch magnet 13, 105 of the indicator mechanism, the lead 40, extending from said magnet 13, to the

magnet 6, of the winding mechanism and the lead 41, extending from said coil 6, to the circuit breaker comprising the contacts 42, and 43, and thence, by the lead 37, to the 5 supply lead 21, as above described. Said circuit breaker contacts 42, and 43, are normally closed to complete the circuit, as shown, but are opened to instantly terminate the winding movement of the lock when the 10 lock member 45, is shifted, from the position shown, in the direction of the arrow marked thereon in Fig. I, which movement occurs when the lock is opened. In order to set the dial 12, to correspond with the position 15 of the wheel 4, it is necessary for the operator at the indicator station to know the precise position of said wheel 4, at the winding station. Therefore, I provide a test circuit comprising the lead 46, extending from 20 the supply lead 22, through the annunciator 47, at the indicator station to the test switch at the winding station, comprising the stationary contact 48, and spring contact 49, the latter being connected by the lead 50, 25 with said lead 37. As shown in Fig. I, said wheel 4, of the winding mechanism is provided with the cam 51, which is coincident with the initial point of said wheel, and which closes said test switch when said 30 cam reaches a certain point in the revolution of said wheel 4; so that when the annunciator 47, is operated by closure of said test switch, the dial 12, may be set with its initial point corresponding with that of the wheel 4.

35 As shown in Fig. II; the winding motor armature 2, has its shaft 52, journaled in the bearing standards 53, extending at its opposite ends from the frame 54. Said shaft 52, has the beveled pinions 55 and 56, respectively engaging the gear wheels 57 and 58, on the clutch shafts 59 and 60, which are journaled in said standards 53, and in the standards 61. Said shafts 59 and 60, are respectively in alinement with the shafts 62 and 63, 40 which are supported in the bearing standards 64, and 65, on said frame 54, and carry the bevel gears 66 and 67. Said bevel gears 66 and 67, are respectively engaged with bevel gears 68 and 69, carried at the respectively opposite ends of the worm shaft 70, which is supported in said bearing standards 64, and also in the bearing standards 71. Said worm shaft 70, carries the worm 73, which is engaged with the wheel 4, which is 45 a worm gear carried by the rotary lock shaft 3. Said clutch shafts 59 and 60, are provided with clutch sleeves 76 and 77, which are free to slide thereon but are caused to turn therewith by the pins 78 and 79, extending into the slots 80 and 81, of said sleeves. Said sleeves 76 and 77, are respectively provided with clutch lugs 83 and 84, arranged to alternately engage the clutch studs 85 and 86, which respectively project 50 from the shafts 62 and 63, in rigid relation

therewith. Said sleeves 76 and 77, are provided with loose collars 88 and 89, pivotally connected by pins 90 and 91, with the clutch shifting lever 92, which is fulcrumed intermediate of its length on the stud 93, extending from said frame 54. The opposite ends of said lever 92, are in operative relation with the clutch shifting magnets 6 and 7, which are disposed in pairs supported by the brackets 95 and 96, extending from said 55 frame 54.

As shown in Fig. IV; the indicator motor armature 10, has its shaft 102, journaled in the bearing standards 103, extending at opposite ends from the frame 104. Said shaft 102, has the bevel pinions 105 and 106, respectively engaging the gear wheels 107 and 108, on the clutch shafts 109 and 110, which are journaled in said standards 103, and in the standards 111. Said shafts 109 and 110, are respectively in alinement with the shafts 112 and 113, which are supported in the bearing standards 114 and 115, in said frame 104, and carry the bevel gears 116 and 117. Said bevel gears 116 and 117, are respectively engaged with the bevel gears 118 and 119, carried at the respectively opposite ends of the worm shaft 120, which is supported in said bearing standards 114, and also in the bearing standards 121. Said worm shaft 120, carries the worm 122, which is engaged with the dial 12, which is a worm gear mounted to turn freely on the stud shaft 123, in said frame 104, and is provided with a circular series of one hundred graduations 124, corresponding with the ordinary tumbler dial of a combination lock. The index 125, projects in stationary relation with said frame 104, in correspondence with the index point of the lock dial. Said clutch shafts 109 and 110, are provided with clutch sleeves 126 and 127, which, though free to slide thereon, are caused to turn therewith by the pins 128, and 129, extending in the slots 130 and 131, of said sleeves. Said sleeves 126 and 127, are respectively provided with clutch lugs 133 and 134, arranged to alternately engage the clutch studs 135 and 136, which respectively project from the shafts 112 and 113, in rigid relation therewith. Said sleeves 126 and 127, are provided with loose collars 138 and 139, pivotally connected by pins 140 and 141, with the clutch shaft lever 142, which is fulcrumed intermediate of its length on the stud 143, extending from said frame 104. The opposite ends of said lever 142, are in operative relation with the clutch shifting magnets 13 and 14, which are disposed in pairs supported by the brackets 145 and 146, extending from said frame 104.

The apparatus above described, as arranged in Fig. I, is adapted to operate a combination lock of which 3, is the tumbler arbor and 4, a wheel corresponding with the ordinary graduated disk by which such an 130

arbor is turned. As shown, the lock arbor 3, is in its initial position with the cam 51, closing the test circuit and operating the annunciator 47, to manifest said position to the operator local to the means for electrically controlling the apparatus as above described. The indicator dial 12, being set in a position corresponding with the initial position of said lock wheel 4, aforesaid, and the switch blade 30, being set, as shown, to simultaneously operate the right hand clutch magnets 7 and 14; both the wheel 4, and the dial 12, are turned synchronously to the right, while the operator holds the switch 23, closed as shown. When said movement has continued until the desired number is reached, the operator may reverse the direction of rotation of said wheel 4, and indicator dial 12, by shifting the switch 20 blade 30, to the left, first breaking the circuit through the leads 31 and 32, and thus disconnecting the right hand magnets 7 and 14, and the clutches controlled thereby. Then, by further movement to the left, said switch blade 30, establishes the circuit through the left hand clutch magnets 13 and 6. When the lock arbor 3, has been thus turned to the desired extent, the operator may disconnect all of the clutch mechanisms 25 and thus terminate the turning movement, by shifting the switch blade 30, to its central position; the two motors continuing to rotate until the operator releases the push button 23, which has been held closed 30 throughout the turning operation aforesaid. However, irrespective of the position of the switch blade 30, the turning movement of the lock arbor is instantly terminated automatically when the lock is opened, because 35 the movement of the lock member 45, consequent upon the opening movement of the lock, breaks the circuit through the clutch magnets, by separating the contacts 42 and 43.

It being understood that my invention 40 may be applied to wind one or more spring arbors of a time lock, suitably connected with the wheel 4, it may be observed that as such use does not require the reversal of direction of rotation of the wheel 4; the left 45 hand clutch magnets 6 and 13, and the circuits connecting them with the other parts of the apparatus may be omitted. In such use of my invention the lock member 45, may be operatively connected with the usual 50 automatic stop mechanism of the time lock so as to break the circuit and terminate the winding movement when the lock is fully wound. The resistance coils 29 and 38, are merely employed to adapt the circuit shown 55 in Fig. I, for connection with an ordinary electric lighting circuit, and it is to be understood that if a battery or other suitable source of energy is employed, said resistance coils may be omitted.

60 I do not desire to limit myself to the pre-

cise details of construction and arrangement herein described, as it is obvious that various modifications may be made therein without departing from the essential features of my invention, as defined in the appended claims. 70

I claim:—

1. The combination with a lock having a rotary wheel; of an indicator having a rotary dial; means operatively connecting said wheel and dial arranged to turn them synchronously in either direction, comprising synchronously operative electric motors respectively local to said wheel and dial; gearing operatively connected with the respective motor armature shafts and comprising counter-shafts respectively provided with worms and engaged with said wheel and dial; shafts extending transversely with respect to said armature shafts and worm shafts and having gearing operatively connecting them; clutch mechanisms upon each of said transverse shafts arranged to render them alternately operative and inoperative; electro magnets respectively local to said clutch mechanisms; and, electric connections, whereby the clutch magnets of said winding mechanism and said indicator mechanism are simultaneously similarly actuated, substantially as set forth. 80

2. The combination with a lock having a rotary member; of an indicator having a rotary member; means operatively connecting said members arranged to turn them synchronously in either direction, comprising synchronously operative electric motors respectively local to said rotary members; gearing operatively connected with the respective motor armature shafts and comprising counter-shafts respectively provided with worms and engaged with said rotary members; shafts extending transversely with respect to said armature shafts and worm shafts; and having gearing operatively connecting them; clutch mechanisms upon each of said transverse shafts arranged to render them alternately operative and inoperative; electromagnets respectively local to said clutch mechanisms; and, electric connections, whereby the clutch magnets of said winding mechanism and said indicator mechanism are simultaneously similarly actuated, substantially as set forth. 100

3. The combination with a lock having a rotary member; of an indicator having a rotary member; means operatively connecting said members arranged to turn them synchronously in either direction, comprising synchronously operative electric motors respectively local to said rotary members; gearing operatively connected with the respective motor armature shafts and comprising counter-shafts respectively provided with means engaged with said rotary members; shafts extending transversely with respect to said armature shafts and counter- 110

130

- shafts and having gearing operatively connecting them; clutch mechanisms upon each of said transverse shafts arranged to render them alternately operative and inoperative; 5 electromagnets respectively local to said clutch mechanisms; and, electric connections, whereby the clutch magnets of said winding mechanism and said indicator mechanism are simultaneously similarly actuated, substantially as set forth.
4. The combination with a lock arbor in operative relation with a worm wheel; of a shaft having a worm engaging said wheel; an electric motor armature shaft extending 10 parallel with said worm shaft; shafts extending transversely with respect to said worm and armature shafts and operatively connecting them at their respectively opposite ends; clutch devices arranged to slide 15 upon said respective transverse shafts; a clutch lever fulcrumed intermediate of its length and having its opposite ends respectively pivotally connected with said clutch devices; electromagnets respectively 20 operatively related to the opposite ends of said clutch lever; and means arranged to energize said clutch magnets, in alternation; whereby said worm wheel may be rotated alternately in opposite directions by rotation 25 of said armature shaft continuously in one direction, substantially as set forth.
5. The combination with a lock arbor; of a worm wheel on said arbor; a shaft having a worm engaging said wheel; an electric motor having an armature shaft extending 30 parallel with said worm shaft; a divided shaft connecting said armature shaft with said worm shaft and comprising aligned relatively rotary sections; clutch mechanism arranged 35 to alternately engage the sections of said divided shaft to turn together and permit them to turn independently; and electrically controlled means arranged to operate said clutch mechanism, substantially as 40 set forth.
6. The combination with a lock arbor; of a worm wheel on said arbor; a shaft having a worm engaging said wheel; an electric motor having an armature shaft extending 45 parallel with said worm shaft; a divided shaft connecting said armature shaft with said worm shaft and comprising aligned relatively rotary sections; clutch mechanism arranged 50 to alternately engage the sections of said divided shaft to turn together and permit them to turn independently; and electrically controlled means arranged to shift said clutch alternately in opposite directions, comprising a lever fulcrumed intermediate 55 of its length; and, electromagnets respectively in operative relation with said lever upon opposite sides of its fulcrum, substantially as set forth.
7. The combination with an electric motor 60 having a rotary armature shaft; of a shaft 65 provided with a worm; means operatively connecting the respectively opposite ends of said armature shaft and worm shaft, comprising divided shafts having axially aligned sections which may be relatively rotated; 70 clutch devices mounted to slide axially on said divided shafts, arranged to alternately connect the aligned sections for rotation together and to free them for independent rotation; and, means arranged to shift said 75 clutch devices alternately in opposite directions, substantially as set forth.
8. The combination with an electric motor having a rotary armature shaft; of a worm shaft extending parallel with said armature 80 shaft and operatively connected therewith at its respectively opposite ends; and, a rotary lock arbor having a worm wheel engaged by said worm shaft, substantially as 85 set forth.
9. The combination with a lock having a rotary member; of an indicator having a rotary member; means operatively connecting said members arranged to turn them synchronously in either direction, comprising synchronously operative electric motors, 90 respectively local to said rotary members; gearing operatively connected with the respective motor armature shafts, and comprising countershafts respectively provided 95 with means engaged with said rotary members; shafts extending transversely with respect to said armature shafts and countershafts, and having gearing operatively connecting them; clutch mechanisms between 100 said motor armature shafts and said countershafts arranged to render said transverse shafts alternately operative and inoperative; electro magnets respectively local to said 105 clutch mechanisms; and, electric connections whereby the clutch magnets of said winding mechanism and said indicator mechanism are simultaneously similarly actuated, substantially as set forth.
10. The combination with a lock having a 110 rotary member; of an indicator having a rotary member; means operatively connecting said members arranged to turn them synchronously, comprising simultaneously 115 operative electric motors respectively local 115 to said rotary members; gearing operatively connected with the respective motor armature shafts, and comprising countershafts respectively provided with means engaged 120 with said rotary members; means arranged 120 to render said countershafts alternately operative and inoperative, including clutch mechanisms between said motor armature shafts and said countershafts; electro magnets respectively local to said clutch mechanisms; 125 and, electric connections whereby the clutch magnets of said winding mechanism and said indicating mechanism are simultaneously synchronously actuated, substantially 130 as set forth.

11. The combination with a lock having a rotary member; of an indicator having a rotary member; means operatively connecting said members arranged to turn them 5 synchronously in either direction, comprising synchronously operative electric motors, respectively local to said rotary members; gearing operatively connected with the respective motor armature shafts, and comprising countershafts respectively provided with means engaged with said rotary members; clutch mechanisms between said motor armature shafts and said countershafts alternately operative to reverse the direction of

rotation of said countershafts; electro magnets respectively local to said clutch mechanisms; and, electric connections whereby the clutch magnets of said winding mechanism and said indicator mechanism are simultaneously similarly actuated, substantially as set forth. 15

In testimony whereof I have hereunto signed my name at Philadelphia, Pennsylvania, this 22nd day of April, 1908.

EDWARD W. MARVEL.
